UNITED STATES PATENT OFFICE.

THEODORE CHARLES DOREDANT, OF NEW ORLEANS, LOUISIANA.

DOOR-FASTENER.

1,111,568.

Specification of Letters Patent. Patented Sept. 22, 1914.

Application filed October 16, 1913. Serial No. 795,487.

To all whom it may concern:

Be it known that I, THEODORE C. DOREDANT, a citizen of the United States, and a resident of New Orleans, in the parish of Orleans and State of Louisiana, have invented a new and Improved Door-Fastener, of which the following is a full, clear, and exact description.

The invention relates to a temporary fastening device adapted for insertion between a door and door jamb, to fasten the door in the closed position and from the inside of a room.

More particularly the invention relates to a device of the indicated character having novel features, including a shank provided with a locking head shaped at one side to project into and be accommodated in the door lock adjacent to the beveled end of the usual latch bolt, the head at the opposite side having a member to be projected laterally into the usual hole in the strike plate on the jamb by the turning of the device, there being a shoulder to engage the strike plate.

On the shank of the device is a pivoted member adapted to be entered between the door and jamb, to prevent surreptitious turning of the device out of engagement with the strike plate.

The novel features of the invention will be further explained in the specific description following.

Reference is to be had to the accompanying drawings forming a part of this specification, in which similar characters of reference indicate corresponding parts in all the views.

Figure 1 is a plan view of the improved fastener applied to a door and door jamb, parts of which, with lock elements thereof, are shown in horizontal section; the fastener device being engaged with the door only; Fig. 2 is a view similar to Fig. 1, but showing the fastener device after having been given a partial turn to be engaged with both the door and jamb; Fig. 3 is a face view of a portion of the edge of the door, showing the improved fastener in side elevation, and Fig. 4 is a perspective view of the locking head.

In the drawings there is indicated a section of a door A, a section of a door jamb B, a portion of a mortise lock C in the door, the latch bolt of which is indicated by the letter D, and the front face plate of which is indicated by the letter c. On the door

jamb is indicated the usual strike plate E having the bolt opening e.

My improved fastener comprises a shank 10 on which is a head designated generally by the numeral 11. The forward end 12 of the head is flat, or essentially so, to lie when in the inner position, close against a wall of the lock casing C in the door, as indicated in Figs. 1 and 2. From the front flat side 12 rearwardly the head 11 is beveled in the direction of the shank, as at 13, and at said beveled portion the head is more or less rounded transversely. At the rear end of the head or the side opposite the flat front 12, there is formed on the head, or on the shank immediately adjacent to the head, a projection 14 the rear surface 15 of which presents a shoulder. The dimensions and the shape of the head at the beveled portion are such that the device may be so disposed that the head will extend into the lock casing C, through the face plate thereof, across the space between the door and the jamb and through the strike plate E on the jamb through the opening e thereof, the projection 14 engaging by the shoulder 15 with the adjacent edge of the strike plate.

In use, the device is first applied to the door by causing the head 11 to press the latch bolt B inwardly so that a portion of said head will be accommodated in the V-shaped space presented with the beveled end of the latch D within the lock casing. The door may now be closed with the fastener device engaging the lock only, as indicated in Fig. 1. A turning movement of the device on its axis through approximately 90°, will dispose the projections 14 on the portion of the head within the opening e of the strike plate, a part of the rounded and beveled portion still being disposed in the lock casing C adjacent to the beveled end of the latch bolt. In this position of the fastener as shown in Fig. 2, the head, it will be seen, extends transversely across the space between the door and jamb, and interlocks with both of the latter, the bolt remaining in the retracted position and being substituted in its latching functions by the head 11. Thus the head 11 is in the form of a crosshead disposed at one side of the shank, the device being plane, or essentially so, at a face of the head, the turning of the device through 90° serving to present the plane side to the strike plate while in engagement with the lock elements of the door, or to so dis-

pose the head as to engage both the door and the strike plate.

In order to prevent the turning of the fastener either by accident or surreptitiously, there is provided on the shank a securing member 16, in the form of a plate pivoted at its outer end, as at 17, to the shank, in the handle end of the latter, and adapted to be fitted so that its forward end will enter between the door and jamb, as indicated in Fig. 3. To insure that the plate will have a jamming fit, there is formed at opposite sides thereof, lugs 18 which are curved laterally toward the inner side, or the side toward the shank, so that when entered between the door and jamb, either projection 18 may be brought against the key to give a wedging action and jam the securing device against the key and the door, or jamb, as the case may be. A second pivoted securing member 16^a may be employed, of the general form of the element 16. Both are broadened from the rear pivoted ends to present broadened free ends, which advantageously, are rounded to facilitate entrance between the door and jamb. The element 16^a has a bodily lateral curvature in a direction away from the shank 10, in order to present a total effective width to permit of its being yieldingly wedged or jammed between a side of the shank 10 and the door or jamb.

Having thus described my invention, I claim as new, and desire to secure by Letters Patent:

- 35 1. A door fastener of the character described, comprising a shank having a cross-head disposed at one side of the shank, one side face of which head is plane, and the opposite side face of which is beveled longitudinally and curved transversely.
- 40 2. A door fastener of the character described, comprising a shank having a cross-head disposed at one side of the shank, one side face of which head is plane and the opposite side face of which is beveled longitudinally at its rear side and curved transversely, the front of the head being essentially flat, and there being a lateral, rear-

wardly facing shoulder at the back of the head at one side.

3. A door fastener of the character described, comprising a shank having a fastener head, said device being adapted to turn on its longitudinal axis, and a securing member pivoted on the shank near the rear end, said securing device having a lug at a side thereof, deflected in a direction toward the shank and transverse to the pivotal movement of the said securing member.

4. A door fastener of the character described, comprising a shank having a fastener head, said device being adapted to turn on its longitudinal axis, and a securing plate pivoted on the shank, near the end of the latter, said plate having lugs at opposite sides thereof, the lugs being curved in the direction of the shank and transverse to the direction of movement of said pivoted plate.

5. A door fastener of the character described, having a shank provided at a forward portion thereof with a lateral fastener head, to hold the door in the closed position, a pivoted member on the shank rearward of the fastener head, said pivoted member having a laterally curved portion and adapted to be turned on its pivot to a forward position to wedge the said member between the shank of a door or door jamb.

6. A door fastener of the character described, having a shank provided at a forward portion thereof with a lateral fastener head, to hold the door in the closed position, a pivoted member on the shank rearward of the fastener head, said pivoted member having at its free end a bodily lateral curvature in a direction transverse to its pivotal movement.

In testimony whereof I have signed my name to this specification in the presence of two subscribing witnesses.

THEODORE CHARLES DOREDANT.
